LIGHT

Jeremiah D. Kennelly, Oak Park, Ill.

Application March 22, 1941, Serial No. 384,615

2 Claims. (Cl. 177—327)

This invention relates to a light or lamp structure.

The structure is useful as a headlight for a locomotive or other vehicle, a signal lamp for a vehicle, a lamp for railway or other crossings and for a great many other uses which will be obvious.

An object of the invention is to provide a light which is effective for providing illumination and at the same time providing beams which swing apart from the main light path as a signal or as means for indicating the presence of the light over wider or an irregular area. Other specific objects and advantages will appear as the specification proceeds.

The invention is illustrated in a preferred embodiment, by the accompanying drawings, in which—

Figure 1 is a rear view in elevation of light apparatus embodying my invention; Figure 2, a top plan view showing the movable lights in aligned position with respect to the other lights; Figure 3, a top plan view similar to Figure 2 but showing two of the lights moved out of alignment with the fixed lights. Fig. 4 is a plan view of the beam pattern formed with the light of the invention; and Fig. 5 is a front elevational view of the beam pattern.

In the illustration given, a circular casing 10 is illustrated which may be provided with a glass lens 11. The casing is provided with a rearwardly extending skirt portion 12 to the rear of which is secured a cross beam 13. Mounted to the rear of the skirt portion 12 is a plate member 14 which serves as a means for retaining the fixed reflectors 15. The plate 14 is cut away at 16 to enable the movable reflectors 17 to oscillate without striking the plate.

Any suitable means for moving or oscillating the movable reflectors 17 may be employed. In the illustration given, the reflector-equipped sockets 18 are supported upon the cross beam 13 by a ball mounted joint 19 or by any other suitable joint. A suitable form of ball bearing joint is illustrated in Figure 9 of my Patent No. 2,221,493. Extending to the rear of one of the joints 19 is a lever arm 20 which is pivotally connected to a cross bar 21. Extending to the rear of the other joint 19 is a lever 20^a which has an intermediate portion connected to the cross strap 21 and its rear extremity connected to a lever 22 driven by the motor. In the illustration given, each of the bars 21 and 22 are connected to the respective parts described by ball and socket joint.

It will be understood, however, that any suitable joint may be employed.

The motor 23 is mounted upon the bracket member 24 carried by posts 25 which are integrally formed with the cross beam 13. Through a train of gears, the motor drives shaft 26 which is provided with an integral drive lever 27 provided with a slot 28. The slot engages a drive pin 29 carried by the lever 22, the pin being provided with a ball and socket joint in the end of the bar 22.

In the operation of the mechanism, the fixed lights throw a beam forward, the reflectors serving to provide a concentrated illuminated path forward of the light. The operation of the motor causes the two movable reflectors 17 and their sockets 18 to move upon the joints 19 with the result that light beams are swung by such reflectors laterally and beyond the pattern of light thrown by the fixed reflectors. The light beams from the movable reflectors pass through the pattern of light from the fixed reflectors first to one side and then to the other. The swinging movement of the reflectors is accompanied by the motor through the rotation of the shaft 26 and the slotted drive bar 27. As the slotted member 27 rotates, the lever 22 swings inwardly and outwardly as illustrated in Figures 2 and 3, thus causing the member 20^a to swing laterally and causing the connecting rod 21 to swing the member 20 also laterally.

It will be noted that the movable reflectors are, for a period of their movement, substantially in line with the other reflectors, the light rays from them being added to the light rays from the fixed reflectors. In the continued movement of the reflectors, however, the rays therefrom emerge to one side of the fixed beam and throw a beam of light across an area not illuminated by the main light beam or pattern. The lateral emergence of the moving beams from the main light pattern signals the presence of the light to motorists approaching from different directions. When the light is mounted upon a locomotive, the sweeping rays emerging from the broad light pattern help to indicate the movement of the locomotive and to warn those driving towards the tracks of the approaching locomotive or other vehicle. The submergence of the signaling lights within the broad main beam helps to increase the effectiveness of the signal beams when they suddenly emerge and pass beyond the main beam or light pattern. At the same time, the laterally moving beams increase the effectiveness of the headlight from the stand-

point of the locomotive engineer in that the moving lights increase the width of illumination as they move laterally beyond the broad light beam.

One of the most effective results obtained from the device as a signal device is the suddenness with which the signal beams strikes the eye of the observer after leaving the main light pattern thrown by the headlight. The submergence of the moving lights within the broad beam serves, in effect, to hide the signal light beams until they suddenly appear beyond the sweep of the main beam. From the standpoint of effective signaling, the sweeping beams are just as effective as if they automatically went on and out while at the same time, the beams provide the advantage of increasing the illumination provided by the fixed reflectors and broadening the general pattern of light.

While I have shown two lights and reflectors mounted for movement laterally, it will be understood that a single movable reflector or more than two movable reflectors may be used and they may be moved in directions other than laterally. I have also found that the movable lights may be effectively moved in opposite or different directions simultaneously with good results, as well as moved in unison to the right and the left, as illustrated.

The foregoing description has been for the purpose of setting forth a specific illustrative

mode of operation and it will be understood that the details shown may be varied widely by those skilled in the art without departing from the spirit of my invention.

I claim:

1. In light apparatus of the character set forth, a light frame, a closely associated group of light bulbs supported in said frame against movement, reflectors about said bulbs and directing the light rays therefrom forwardly in one general broad light pattern, and a pair of light-bulb-equipped reflectors closely associated with said first mentioned group of light bulbs but mounted in said frame for lateral movement, and power operated means for swinging said movably mounted reflectors in unison first totally within

10 and then laterally beyond said general light pattern.

2. In light apparatus of the character set forth,

20 a light frame, a group of light-bulb-equipped reflectors fixedly supported in said frame, the reflectors thereof drawing the light rays from said bulbs in a forwardly extending light pattern, a plurality of light-bulb-equipped reflectors mounted within said frame for oscillatory movement, and power operated means carried by said frame for swinging said movably mounted reflectors first into a submerged position totally within and then laterally beyond said general

25 30 light pattern.

JEREMIAH D. KENNELLY.
